UNITED STATES PATENT OFFICE.

BERT ANDERSON, OF NEW ORLEANS, LOUISIANA, ASSIGNOR TO F. E. ANDERSON, M. D. ANDERSON, W. L. CLAYTON, AND B. CLAYTON, A COPARTNERSHIP DOING BUSINESS AS ANDERSON, CLAYTON & CO.

BALE TIE.

Application filed January 16, 1923. Serial No. 612,943.

To all whom it may concern:

Be it known that I, BERT ANDERSON, a citizen of the United States, residing at New Orleans, in the parish of Orleans and 5 State of Louisiana, have invented new and useful Improvements in Bale Ties, of which the following is a specification.

The present invention relates to improvements in bale ties, and has for its object to 10 provide a simple form of tie, which may be readily applied to packages, the improvements being particularly applicable for use in maintaining pressed bales of cotton in compressed condition.

15 Among the objects of the invention may be mentioned that of providing a tie which can be readily applied to a bale while in the baling press and have the ends easily and securely interlocked.

20 A further object is to provide a form of lock or connection between the ends of the tie, which will not be liable to become detached when the bale is handled after being removed from the press.

25 Other objects and advantages will appear from the following description of the embodiment of the invention illustrated in the accompanying drawing.

In the drawings:

30 Figure 1 is an elevation showing a portion of a bale and the jaws of a press bearing thereon, and two ties embodying the present invention being shown.

Figure 2 is an elevation at right angles to Figure 1 on a smaller scale.

35 Figure 3 is a side view, on an enlarged scale, of the ends of the improved tie showing the parts in process of engagement.

Figure 4 is an elevation of the parts 40 shown in Figure 3 of the inner face of the tie or that face which lies against the bale.

Figure 5 is an elevation of the outer face of the engaged ends of the tie.

45 Referring to the drawings, wherein like reference characters designate corresponding parts in the several views, B designates a bale of cotton, for example, which is shown as arranged between upper and lower press members P, P' and about which the bale tie of the present invention is secured.

The tie comprises a metal strip or band of sufficient length to encircle the bale B and provided at its ends with means for en-

gaging, one with the other, so that it can be retained in position about the bale to permit handling thereof and prevent undue expansion of the compressed contents thereof. 55

In order to strengthen the end, interlocking, portions of the tie, the body thereof is doubled upon itself at each end as indicated 60 at 1, and these double portions are firmly connected as by spot-welding or a suitable rivet 2.

In the body of the tie adjacent one end are provided a plurality of elongated slots 3 and 65 the other end of the tie is provided with a suitable head adapted to be passed through either slot and engage with the walls thereof to prevent separation of the ends, the shape and manner of providing such head being 70 more particularly hereinafter described.

The slots are preferably of the form illustrated, each having a gradually reduced section toward its end away from the terminal end of the band adjacent to which they are 75 provided, such slots being of sufficient length to permit the head at the opposite end of the tie to be passed therethrough by arranging the said ends in the relative positions shown at the right hand side of Figure 1. 80

The reinforced portion of the other end of the tie has a portion thereof at a point removed from its end bent or rolled upon itself transversely of the length to provide a neck-like portion 4, which will preferably 85 be slightly tubular, and this tubular or rolled neck portion 4 is connected by a slightly curved section 5 with a flat terminal section 6. The rolled neck portion 4 is of slightly less diameter than the rectangular portion of 90 the slots 3 so that it can be passed therethrough and the flat terminal portion 6, as shown in Figures 1, 4 and 5, is of the same width as the body of the tie.

As no portion of the fastening means for 95 securing the ends of the tie together is of greater width than the body of the tie, it will be seen that the tie may be very quickly and easily applied to a bale. Both ends can be simultaneously passed through the 100 grooves p in the press plates P, P' from one side of the press, as shown in Figure 2, and when the head 6 of one end has been passed through the proper aperture 3 in the other end of the tie, the two tie sections can be turned from the position shown 105

at the right hand side into that shown at the left hand side of said figure when the two ends will be securely interlocked.

As shown in Figures 1, 4 and 5, when the tie ends are thus interlocked about a bale there are no undesirable projections liable to catch on other articles or to be struck in such manner as to effect disengagement of the fastening between the tie ends. The only projecting portion is the rounded or curved neck section 4 and all parts of the fastening are within the side lines of the body of the tie.

The expansive force exerted by the compressed material in the bale operates to draw the two ends from each other in the direction of the length of the adjacent end sections so that there is a firm and positive lock formed between the enlarged, flattened terminal portion 6 of the one end and the aperture engaged adjacent the other end of the tie.

It is believed that the operation and advantages of the tie will be readily appreciated from the foregoing description.

Having thus described the invention, what is claimed and desired to be secured by Letters Patent is:

1. A bale tie having each of its ends doubled back a short distance and secured to the body, one of the ends thus re-enforced being provided with a plurality of elongated slots, the other end being provided with a head integral with the tie and adapted to lock into one of the slots at the other end when placed around a bale.

2. A bale tie having each of its ends doubled back a short distance and secured to the body, one of the ends thus re-enforced being provided with a plurality of elongated slots, the other end being provided with a short tubular section terminating in a flat portion and forming a T-shaped head adapted to pass through any of the slots in the tie adjacent the other end to secure the ends of the tie together as they are brought into overlapping relation.

3. A bale tie having its ends re-enforced by being doubled back for a short distance and secured to the body and provided with fastening means formed integral with the body, no portion of said fastening being wider than the tie, so that either or both ends are adapted to pass through slots in press heads.

4. A bale tie provided adjacent one end with a plurality of elongated slots, the other end being shaped to provide a short, longitudinally extending, tubular section that terminates in a relatively flat transversely

extending head that projects beyond the sides of the tubular section.

5. A bale tie provided adjacent one end with a plurality of elongated slots, the body of the tie adjacent its other end being bent upon itself to provide a relatively narrow neck that extends longitudinally of the tie and is slightly bowed or bent in the direction of its length, said neck portion terminating in a transversely extending flat head, for the purpose described.

6. A bale tie having its ends re-enforced by doubling for a short distance, one end being provided with a plurality of elongated slots, the other end having a short tubular section terminating in a flat portion forming a T-shaped head, no portion of which is wider than the body of the tie.

7. A bale tie having a plurality of elongated slots formed therein near one end, the widest portion of each slot being toward the adjacent end, the tie adjacent the other end being bent upon itself transversely of its length to form a relatively narrow neck and terminating in a flattened portion of greater width than the slots.

8. A bale tie provided at one end with a plurality of elongated slots, the other end having a short tubular section adjacent the end, which is flattened and forms a T-shaped head adapted to be passed through any of the slots.

9. A bale tie provided at one end with a plurality of slots and having at its other end a flat terminal portion, the body of the tie adjacent said flat terminal being rolled or bent upon itself transversely of its length to form a neck that constitutes a T-shaped head with the flat terminal, for the purpose described.

10. A bale tie having a plurality of openings at one end, the other end of the tie being bent upon itself transversely of its length at a point removed from its end, to form a relatively narrow strengthened neck portion terminating in a head adapted to engage the openings at the other end of the tie.

11. A bale tie having a plurality of openings at one end, the other end of the tie being folded lengthwise and bent upon itself transversely of its length at a point removed from its end, to form a reinforced relatively narrow strengthened neck portion terminating in a reinforced multi-ply head adapted to engage the openings at the other end of said tie.

In testimony whereof I have hereunto set my hand.

BERT ANDERSON.
